UNITED STATES PATENT OFFICE

2,609,106

CAP TRANSFER MECHANISM FOR DRYING OVENS

Ernest A. Tesch, Jr., Chicago, Ill., assignor to Phoenix Metal Cap Co. Inc., Chicago, Ill., a corporation of New York

Application August 25, 1948, Serial No. 46,067

4 Claims. (Cl. 214—1)

1

The invention relates to new and useful improvements in a cap transfer mechanism for automatically removing caps in groups from a conveyer and placing the same on the trays of a drying oven.

An object of the invention is to provide a transfer mechanism wherein a series of cap carrying devices are so moved and timed as to simultaneously engage and lift a group of caps from a conveyer while it is moving and simultaneously place said lifted caps on a tray of a drying oven while the tray is moving.

A further object of the invention is to provide means for independently supporting cap carrying devices so that each device may be moved in a circular path extending first over a conveyer for receiving the cap and thence over a tray for placing the cap thereon and wherein each lifting device is lowered to pick up the cap and again lowered for placing the cap on the tray.

Another object of the invention is to provide a mechanism for moving said lifting devices so that each device is accelerated to the speed of travel of the caps during the picking of the caps from the conveyer and decelerated to a substantially stand-still while placing the caps on a tray.

A still further object of the invention is to provide each cap carrying device with a suction cup and a suction control valve that is opened just prior to the cup reaching the cap for quickly lifting the cap into engagement with the cup and also a suction control valve that is opened for releasing the suction when the cap is properly positioned for placement on the tray.

These and other objects will in part be obvious and will in part be hereinafter more fully disclosed.

In the drawings, which show by way of illustration one embodiment of the invention:

Figure 1 is a sectional view through one form of cap or lid that may be coated and then dried in a drying oven;

Figure 2 is a front view of the left hand portion of the housing for the transfer mechanism with certain parts removed and others broken away or sectioned in order to show the inner mechanism which transfers the caps from a conveyer to the trays of the drying oven;

Figure 2a is a front view of the right hand portion of said housing with parts removed and parts broken away to show the inner mechanism;

Figure 3 is a plan view of said housing with parts broken away and parts in section in order to show the inner structure;

2

Figure 4 is an end view of said housing for the transfer mechanism with parts removed to show the inner structure;

Figure 5 is a sectional view on the line 5, 5 of Figure 3;

Figure 6 is a sectional view on the line 6, 6 of Figure 2, and Figure 5;

Figure 7 is a sectional view on the line 7, 7 of Figure 2;

10 Figure 8 is a vertical sectional view through the cap carrying devices on an enlarged scale;

Figure 9 is a view showing in section the housing for the cap carrying devices, a portion of the oven conveyer, and the trays supported thereon with the cap carrier shown in full lines as having lifted a cap from the conveyer associated with the coating machine and in broken lines as having placed the cap on a tray of the conveyer associated with the drying oven;

20 Figure 10 is a front view of the cam for shifting the planet gears to accelerate or decelerate the rotating movements of the cap carrier;

Figure 11 is a view in perspective showing the spider for supporting the planet gears and the yoke which is attached to the spider for shifting the planet gears in one direction for accelerating the movement imparted to spindles and in the other direction for decelerating the movement of the spindles.

30 In my copending application, Serial No. 15,822, filed March 19, 1948, now Patent No. 2,600,138, I have shown and described a mechanism for applying a sealing gasket to caps or lids for containers.

35 The caps which are to be coated are of the usual type employed in the sealing of jars or the like. The cap is die-shaped so as to provide a cap with a peripheral channel for a sealing gasket which contacts with the sealing lip of the jar for closing and sealing the jar. The coating mechanism disclosed in my copending application includes a stack holder for the caps, a conveyer for conveying the caps from the stack holder through the coating means. There are also devices for removing the caps one at a time

40 from the stack holder and placing the same on the conveyer with the channel of the cap facing upwardly. The conveyer carries the cap across the coating face of a coating roll so that the peripheral flange of the cap will engage and scrape coating material from the roll. During its travel along the coat roll, the cap is rotated so that the channel will be uniformly filled with the coating material.

45 This all takes place during the movement of the conveyer and while the caps are on the conveyer.

45 The caps which are to be coated are of the usual type employed in the sealing of jars or the like. The cap is die-shaped so as to provide a cap with a peripheral channel for a sealing gasket which contacts with the sealing lip of the jar for closing and sealing the jar. The coating mechanism disclosed in my copending application includes a stack holder for the caps, a conveyer for conveying the caps from the stack holder through the coating means. There are also devices for removing the caps one at a time from the stack holder and placing the same on the conveyer with the channel of the cap facing upwardly. The conveyer carries the cap across the coating face of a coating roll so that the peripheral flange of the cap will engage and scrape coating material from the roll. During its travel along the coat roll, the cap is rotated so that the channel will be uniformly filled with the coating material.

50 This all takes place during the movement of the conveyer and while the caps are on the conveyer.

The present improvement has to do with the transfer mechanism for taking a group of caps from this conveyer while it is moving and depositing the caps simultaneously on a tray of a drying oven.

This transfer mechanism includes a series of cap carriers mounted for rotation so that the carriers are first positioned over the caps on the conveyer and moved into engagement therewith and then away from the conveyer for lifting the caps therefrom. A suction means is provided for holding the caps to the carriers. After the caps have been lifted from the conveyer by the carriers they are moved so as to simultaneously place the caps over an oven drying tray. Then the carrier is lowered for placing the caps on the tray while the tray is moving. The suction holding the cap to the carrier is released so that the caps drop from the carriers onto the trays. The means for rotating the carriers includes devices for accelerating the movement of the carriers to the speed of the traveling conveyer as the carriers engage the caps and then the movement of the carriers are decelerated to a substantially stand-still as the caps are placed on the tray.

It is believed that the invention will be better understood by a detailed description of one embodiment of the invention in mechanisms.

In Figure 1 of the drawing, there is shown a cap or lid 10 which is of the usual construction. It is die-shaped so as to provide a channel 11 having a peripheral flange 12. The channel is provided with a sealing composition 13 which is of a character that can be flowed into the channel and uniformly fill the same. This is accomplished while the cap is upside down as shown in Figure 1. While the cap is still upside down it is passed through a drying oven so that the volatiles in the coating composition will be driven off.

In the copending application supra, caps of the character shown in Figure 1 are moved one at a time from the stack and placed on a conveyer. The conveyer is so associated with a coating roll that the cap will be moved lengthwise of the face of the coating roll with the flange 12 in engagement with the coating so as to scrape the coating from the roll into the channel.

The conveyer for the caps is illustrated in Figure 9 at 14. The conveyer consists of links 15 forming an endless chain, which links support flat plates 16 on which the caps rest in spaced relation to each other. This conveyer is moved continuously without stopping.

A portion of the drying oven conveyer is shown in Figures 4 and 9. The drying conveyer consists of links 17 joined in an endless chain running over suitable sprockets 18, some of which are shown in Figure 9.

There is a chain at each side of the oven and mounted between the chains and carried thereby are trays 19. Certain of the links are provided with pivot pins 20. The trays each have end flanges 21 slotted at 22 to receive a pivot pin. Rollers 23, 23 are mounted on each tray. These rollers run on tracks after the conveyer enters the drying oven, thus taking the weight of the trays off the conveyer chain.

As shown at the right in Figure 9, the tray designated T is moving from a horizontal path of travel upwardly along a vertical path of travel, and the tray is turned on its pivotal support so as to be retained in a horizontal position.

The tray indicated at T' has reached the position where the caps are loaded on the same. At this particular position in its travel the tray has

ceased its vertical movement and is moving horizontally into the oven.

It is understood that there are numerous trays which are loaded with caps one after another and then the caps on the trays pass through the oven for the drying of the gasket composition. Each tray is of a length so that a group of caps may be placed on the tray side by side in the lengthwise direction of the tray.

10 There are a series of cap transfer devices which are similar in construction and operation. These cap transfer devices simultaneously lift a group of caps from the conveyer 14 and place the group of caps so lifted on a tray of the drying oven. 15 These cap transferring devices as noted are all similar in construction and the description of one will answer for the others.

Mounted on the front wall 24 of the oven is a housing 25 including an upper wall 26 and an 20 intermediate wall 27. Mounted in the intermediate wall 27 is a bearing 28. Carried by the upper wall 26 of the housing is a depending bearing rib 29 in which is mounted a rotating sleeve shaft 30. This sleeve shaft carries a spiral gear 31 which meshes with a worm gear 32 carried by a shaft 33. Mounted in this sleeve shaft 30 for rotation therewith and for endwise movement therein is a supporting shaft 34 for the cap carrier.

30 The cap carrier includes an arm 35 carried by a sleeve 36 which is fixed to the lower end of the shaft 34. This arm 35 extends radially and downwardly from the shaft 34. Said arm has a depending member 37 into which is threaded a 35 cap carrying head 38 provided with a suction cup 39 of flexible material. The cup is secured to the head by a retaining member 40 which is threaded into the head and grips the cup 39.

Attached to the upper side of the wall 26 is a 40 cap 41 carrying a header 42. This header is so dimensioned that the shaft 34 can move up into the header without contacting the same. Sealing gaskets 43 are provided for making the tight joint between the header and the shaft. The shaft 45 has a central passage 44 extending lengthwise thereof and connected to the header at the upper end. The lower end of this passage is closed by a suitable stud 45.

The arm 35 includes likewise a passage 46 50 which is connected with the passage 44. The passage 46 in the arm 35 is counterbored at 47 to receive a valve and to provide a valve seat 48.

Mounted in the counterbore portion of the passage 46 is a valve 49. The valve is provided 55 with a stem 50 having radially projecting ribs which are guided in the passage 46. Said passage has an enlarged portion in which is located a spring 51 which bears against the valve and normally tends to hold the valve open.

60 There is a passage 52 leading from the counterbore 47 to a cylindrical passage 53 in the depending member 37. This passage extends into the cap carrying head 38 and terminates in a valve seat 54. The valve 55 is adapted to engage 65 the valve seat and close the passage.

A spring 56 bears on the valve 55 for holding it closed. Said valve 55 has a depending stem 57 with a rounded end 58 that normally projects below the suction cup 39. The header 42 is connected to a suitable source of vacuum creating apparatus and is maintained under vacuum. When the suction cup is moved into engagement with the cap the stem end 58 of the valve 55 first contacts the cap and the valve is lifted so that the cup is connected to the source of suction, and

as soon as the cup engages the cap, the cap will be gripped by the suction so that it can be lifted.

The arm 35 has threaded into the lower end thereof an adapter 58. This adapter is provided with a valve seat 60 at its inner side. Attached to the valve stem 50 is a valve 61 having a stem 62 which projects beyond the adapter when the valve is closed.

A spring 63 is placed between the valves 49 and 61. The valve 49 is mounted for free movement on the stem and is normally held in engagement with a shoulder 64 on said valve stem 50. When the projecting end of the stem 62 is pressed upon, the valve 61 will be moved away from its seat and the valve 49 will be moved into contact with the seat 48, thus closing off the suction passage in the arm 35 and opening the passage 52 leading to the suction cup, and thus connecting the passage or chamber 53 with the atmosphere and releasing the suction on the cup so that the cap will drop from the cup.

The shaft 34 is moved endwise by an arm 65 fixed to the shaft 66. The shaft 34 carries a collar 67 having an annular groove 68 therein. Each arm 65 is provided with trunnions 69 at each side thereof. (See Figure 3.) The trunnion 69 on adjacent arms engage the recess 68 of the collar 67 so that the shaft 34 is moved endwise without the slightest binding of the shaft in its bearings. The shaft 33 has imparted thereto a variable speed in each cycle of rotation of the cap carrier. When the cap carrier is moving over the cap on the conveyor, the cap carrier is moving in the same direction as the conveyor. While the carrier is directly over the cap the shaft 66 is oscillated so as to move the suction cup into engagement with the cap. The suction controlling valve 55 is opened and the cap attached to the cup and then the carrier is lifted by an upward oscillation of the lever arm 65. When the cap has been conveyed around to a point directly over the tray, the shaft 33 in its rotation is brought to substantially a stand-still, and as it approaches this stand-still position the arm 65 lowers the cap carrying head to a position close to the tray. At this time the valve stem 62 engages a cam plate 70 which opens the valve 61 and releases the suction on the cup, thus releasing the cap so that it drops onto the tray.

Extending from the oven is an actuating shaft 71 which is coupled to a shaft 71^a by a timing device 71^b. The shaft 71^a drives the conveyor 14 for the caps. Also extending from the oven is an actuating shaft 72 which operates the cap carrying devices. This actuating shaft 72 is connected to a spiral gear shaft 73 by a timing device 74.

Mounted in the housing is a shaft 75. Said shaft is mounted in a bearing 76 carried by the outer wall of housing 77, and also a bearing 78 carried by the inner wall of the housing for the driving gear mechanism. Mounted on this shaft 75 is a sleeve 79 which is free to rotate on the shaft. The sleeve carries a member 80.

A worm gear 81 and a cam disc are bolted to the member 80 to rotate therewith. Thus it is that the spiral gear 73 rotates the worm gear 81 and imparts rotation to the sleeve 79. The cam disc is supported by this sleeve and is keyed thereto.

Mounted on the end of the shaft 66 is an arm 83, said arm carries a roller 84 which runs in a cam groove 85 in the face of the cam disc 82. This cam groove has concentric sections separated by sections which are offset radially in-

wardly as indicated at 86. It is this section 86 of the cam groove which operates through the lever arm 83 to oscillate the shaft 66 and thus raise and lower the arm 65 and the shaft 34 on which the cap carrying devices are mounted.

It will be understood that this shaft 66 is common to all the cap carrying units, and will simultaneously raise and lower each cap carrying device. This is what moves the cap carrying device downwardly for engagement with a cap on the conveyor, and thence lifts it off from the conveyor and after it is moved to a position over the tray it lowers the cap carrying device until the caps are positioned for placement on the tray.

Also mounted on the member 80 is a cam disc 87. This cam disc 87 is likewise keyed to the sleeve 79 and rotates therewith. Mounted on this sleeve 79 is a sun gear 88 which is keyed to the sleeve and rotates therewith. Mounted on the shaft 75 and keyed thereto for rotation with the shaft is a radially extending disc 89. An internal gear 90 is bolted by suitable bolts 91 to this disc 89.

Disposed between the internal gear 90 and the sun gear 88 are planet gears 92. There are four planet gears and they each mesh with the internal gear and also with the sun gear. These planet gears are in turn mounted on stud shafts 93 carried by a spider 94, supported by a sleeve 95 mounted on the hub of the disc 89, but free to rotate or oscillate on said hub. In other words, this spider does not rotate with the internal gear. Three of the stud shafts 93 are mounted on a yoke 96 and are bolted to the spider 94. Said yoke member 96 carries an arm 97. Pivoted to the outer end of the arm 97 is a link 98. This link at its other end is pivoted to an actuating lever 99 which in turn is pivotally mounted at 100 on suitable supporting lugs 101. This actuating lever arm 99 carries a roller 102 running in a cam groove 103 in the cam disc 87.

The shaft 75 extends through the bearing 78 and is connected by a suitable timing mechanism 104 to the shaft 33 and it is on this shaft 33 that the driving worm gears 32 for the cap carrying units are mounted.

The sun gear 88 is rotated in a counter-clockwise direction. This will cause the planet gears to rotate in a clockwise direction and also the internal gear to rotate in a clockwise direction. The cam 87 in Figure 10 has been divided into sections and the operation of the cam on the roller 102 for shifting the spider will be described in detail. The cam groove has a concentric section A extending from the radial line a-x to the line b-x. The cam groove also has a concentric section B extending from the radial line c-x to the radial line d-x. Between these sections A and B on the right of Figure 10 is an eccentric section C. The cam rotates in the direction of the arrow and the roller 102 is being moved by the eccentric portion of the cam C outwardly away from the center of the cam and this will shift the spider in a clockwise direction. The shifting of the spider in a clockwise direction accelerates the speed of rotation of the internal gear, and this in turn will accelerate the speed of rotation of the cap carrier.

The normal speed of the cap carrier is slightly less than the speed of the conveyor. This acceleration of the normal speed of the cap carrier occurs as the cap carrier is moving over the conveyor, and the acceleration is sufficient so that the cap carrier will move substantially at the same speed as the conveyor when over the conveyor. At this time the cam groove 85 in the cam

disc 82 will operate to oscillate the lever 83 and thus oscillates the shaft 66 and causes the cap carrier to move downwardly so that the suction cup is sufficiently close to the cap that the valve will be opened and the cap attached to the cup by suction.

In Figure 10, the roller 102 is shown at the position in the cam groove at the time of pick up of the cap. As the cam 87 continues its rotation the roller 102 will continue to shift the spider to the end of its oscillating stroke. The concentric portion B then operating on the roller 102 will cause the spider to dwell for a short time at the end of its oscillating stroke. The eccentric section D of the cam groove 103 then contacts the roller 102 and moves it inwardly toward the center of the cam. This shifts the spider in a counter-clockwise direction. This shifting of the planet gears in a counter-clockwise direction decelerates the movement of the internal gear and in turn decelerates the speed of rotation of the cap carrier.

The eccentricity of the section D is so designed that the deceleration of the rotation of the cap carrier is such that the cap carrier will be brought briefly to substantially a stand-still when the cap carrier is over the tray on which the cap is to be deposited. At this time the cam groove 85 in the cam disc 82 operates to oscillate the shaft 66 and move the cap carrier to a position close to the tray and the breaking of the suction by opening of the release valve causes the cap to drop onto the tray.

The spider continues its oscillation in a clockwise direction until the radial line a-x reaches the roller and while the roller is passing through the concentric portion A of the cam groove 103 the spider will remain substantially without shifting, and then when the roller reaches eccentric section C, the spider will be oscillated again in a clockwise direction and the next cycle of operation formed. It is understood that the accelerating and decelerating movements are imparted simultaneously to all of the cap carriers, and they will move so as to lift the group of caps simultaneously from the conveyer and simultaneously deposit the group of lifted caps on a tray.

It is noted that by the mechanism described above, applicant has provided means for moving a group of caps from a continuously traveling conveyer, and wherein said lifting mechanism will move over a tray and simultaneously deposit the lifted caps on the tray. This all occurs while the tray is moving. By multiplying the number of cap lifting devices which operate as a group for transferring the caps, the speed of the machine has been greatly increased.

It is obvious that many changes in details of construction and the arrangement of the parts may be made without departing from the spirit of the invention as set forth in the appended claims.

I claim:

1. A cap transfer mechanism for lifting a group of caps from a moving conveyer and placing the same on a moving oven drying tray comprising a series of cap carriers independently mounted for rotation about a vertical axis and movement longitudinally of said axis, mechanism for rotating said carriers so as to position the same first over the conveyer and thence over the tray, and means for lowering said carriers into engagement with the caps on the conveyer and again for lowering said carriers for placement of the lifted caps on a tray, an actuating shaft connected to each carrier for rotating the same, an internal gear connected

to said actuating shaft, a sun gear disposed within said internal gear and planet gears for imparting rotation of the sun gear to the internal gear, means for supporting said planet gears whereby they may be shifted about the axis of the sun gear, and an actuating cam for shifting the planet gears so as to accelerate the movement of the carriers to the speed of movement of the conveyer while lifting the caps from the conveyer and for shifting said planet gears so as to decelerate the movement of the carriers to a substantially standstill for placing the caps on a tray.

15 2. A cap transfer mechanism for lifting a group of caps from a moving conveyer and placing the same on a moving oven drying tray comprising a series of cap carriers independently mounted for rotation about a vertical axis and movement longitudinally of said axis, mechanism for rotating said carriers so as to position the same first over the conveyer and thence over the tray, and means for lowering said carriers into engagement with the caps on the conveyer and again for lowering said carriers for placement of the lifted caps on a tray, an actuating shaft connected to each carrier for rotating the same, an internal gear connected to said actuating shaft, a sun gear disposed within said internal gear and planet gears for imparting rotation of the sun gear to the internal gear, means for supporting said planet gears whereby they may be shifted about the axis of the sun gear, and an actuating cam for shifting the planet gears so as to accelerate the movement of the carriers to the speed of movement of the conveyer while lifting the caps from the conveyer and for shifting said planet gears so as to decelerate the movement of the carriers to a substantially standstill for placing the caps on a tray, each carrier having a suction cup, a control valve opened by engagement with the cap and a control valve open to break the suction for depositing the cap on the tray.

35 3. The combination of a movable conveyer for supporting coated caps, traveling trays for supporting a group of caps while oven drying the same, a transfer mechanism for simultaneously removing the group of caps from the conveyor while it is moving and simultaneously placing the lifted group on a tray while the tray is moving, said transfer mechanism including a series of cap carrying devices independently mounted for rotation about vertical axes, said axes being arranged in a line parallel with the line of travel of the conveyor and at right angles to the line of travel of the trays and positioned so that said devices will simultaneously move over the conveyor and thence over the tray, each cap carrying device being movable endwise of its axis for engagement with the caps on the conveyor and for placement of the caps on the tray, an actuating shaft common to said cap carrying devices for rotating the same, a mechanism for rotating said actuating shaft including devices for accelerating the rotation of the carrying devices to the speed of travel of the caps while picking up the caps from the conveyor and for decelerating the rotation of said devices to a substantial standstill while depositing the caps on a tray.

4. The combination of a movable conveyer for supporting coated caps, traveling trays for supporting a group of caps while oven drying the same, a transfer mechanism for simultaneously removing the group of caps from the conveyor while it is moving and simultaneously placing the lifted group on a tray while the tray is moving, said transfer mechanism including a series of cap carrying devices independently mounted for rota-

tion about vertical axes, said axes being arranged in a line parallel with the line of travel of the conveyor and at right angles to the line of travel of the trays and positioned so that said devices will simultaneously move over the conveyor and thence over the tray, each cap carrying device being movable endwise of its axis for engagement with the caps on the conveyor and for placement of the caps on the tray, an actuating shaft common to said cap carrying devices for rotating the same, a mechanism for rotating said actuating shaft including devices for accelerating the rotation of the carrying devices to the speed of travel of the caps while picking up the caps from the conveyor and for decelerating the rotation of said devices to a substantial standstill while depositing the caps on a tray, each cap carrying device having a suction cup, a control valve opened by engagement with the cap, and an

independent control valve opened to break the suction when the cap carrying device is over the tray.
